FIG. 2

Inventor
Jack P. Fullilove

By James M. Ernest

Attorney

UNITED STATES PATENT OFFICE

2,213,491

INSECTICIDE DISPENSER

Jack P. Fullilove, Shreveport, La.

Application June 10, 1939, Serial No. 278,539

5 Claims. (Cl. 91—49)

This invention relates to an improved insecticide dispenser of the type designed to be rotatably mounted on an ambulatory carrier for movement into contact with field plants or the like against which its contents are to be discharged.

The only known prior devices of this type are disclosed in United States Letters Patents, No. 1,504,818 and No. 2,158,115, granted to me on August 12, 1924 and May 16, 1939 respectively, in both of which one or more liquid dispensers of drum-like form is disposed on a horizontal axis for rotation in a direction reverse to that of the vehicle wheels. The object in most instances is to mop the undersides of the plant leaves with poisonous liquid that flows from the drum interiors to their outer cylindrical surfaces.

In the last issued patent, No. 2,158,115 there is shown a cylindrical drum having a series of peripheral annular ridges separated by a series of perforated annular channels, with a layer of cloth or the like tied around the drum to receive liquid from the drum, the cloth serving as a "mop" for directly applying the liquid to the plant leaves. This patented form of dispenser is entirely satisfactory under some conditions and can be utilized with a reasonable degree of success under all conditions, but it leaves something to be desired where the liquid flow must be controlled or regulated accurately by an inexperienced operator.

Therefore, it is the primary object of the present invention to devise a mopping type of liquid dispenser in which there is a free liquid flow around the periphery of the container and in which the mop is uniformly wetted by the limited quantity of liquid that is freely supplied to it.

It is another major object of this invention to provide a method and means for easily regulating or varying the flow of liquid in a device of the character under discussion. This object preferably is accomplished in association with accomplishment of the preceding object.

These and more detailed and related objects of my invention will clearly appear upon a study of the following full description when taken in conjunction with the accompanying drawing and the appended claims. In the drawing:

Figure 1 is an elevational view of a preferred form of the present invention with its channel-bridging screen in partial section and with its mop cloth shown only partially applied.

Figure 2 is an end view of the dispensing unit of Figure 1, with the mop cloth fully applied and tied in position.

Figure 3 is a view similar to Figure 1 and showing the same embodiment with the mop partially cut away and with the screen partially cut to show a flow regulating means.

Figure 4 represents a cross section taken on the plane of line 4—4 in Figure 3 with the mop removed.

With continued reference to the drawing, wherein like characters are employed to designate like parts the dispenser per se consists essentially of a hollow drum D that is closed except for perforations yet to be described, a channel-bridging means in the form of a cylindrical screen S, and a mop or applicator M that encompasses the screen.

The drum is designed to be mounted for rotation with a shaft 5 that is disposed transversely of a vehicle (not shown) at a suitable distance above the ground and driven by any suitable mechanism such, for example, as that shown in the above mentioned patents. To this end the illustrated form of dispenser has a hollow sleeve 6 extending axially therethrough in sealed relation to the drum ends, this sleeve receiving the shaft 5 and being adjustable axially of the latter by means of a set screw 7. As previously stated, it usually is preferable that the drum rotate reversely to the vehicle wheel or wheels so that the periphery of the dispenser will wipe the undersides of the plant leaves.

The drum forms a reservoir for a plant treating material such, for example, as a poisonous liquid solution and it has a filler cap 8 for adding and replenishing the supply of material. Radial discharge of the material takes place through a plurality of ports 9 that open outwardly and that are located within a series of channels or depressions 10 which separate a series of annular ridges 12. The purpose of this arrangement is to cause the insecticide to trickle into the channels and then spread circumferentially within said channels so that substantially the entire drum surface is uniformly wetted with the object of thoroughly and uniformly soaking the mop M. It is desirable that two or more ports 9 be provided for each channel, and preferably all of the ports of the several channels will be grouped at one side of the drum so that when the vehicle is idle the groups of ports may be rotated to the top to prevent fluid discharge.

The mop M consists of a sheet 13 of soft absorbent fabric or the like wrapped around the drum and tied circumferentially with two or more flexible cords 14. It is essential only that two cords, one for each end be used in order to

5 preclude excess leakage in an axial direction along the cylindrical part of the drum. The mop 10 may take the form of a prefabricated cylindrical sleeve having elastic ends that snugly engage the drum ends. Before the mop M is added to the assembly, however, the screen S is interposed to form a bridgework that prevents the fabric from entering and clinging to the channels to interfere with free liquid circulation and/or 15 choke the ports 9.

10 The screen S preferably comprises a simple wire screen material either preformed in the shape of a cylindrical sleeve of adequate length or applied in the form of a sheet that has its 15 edges interlocked or overlapt after it has been bent to cylindrical shape. The edges and the ends of the screen may be soldered together and/or to the drum for permanence. The material and form of this device may vary within 20 wide latitudes, the only prerequisites being that it must permit free and uniform radial flow of the liquid and that it must have sufficient rigidity to hold the mop fabric away from the bottoms of the channels 10. Therefore, it may consist of 25 a hardware cloth of about $\frac{1}{2}$ inch mesh size, or the equivalent in perforated sheet metal, or the like. It is shorter, of course, than the mop so that the mop fabric may be tied into direct sealing contact with the drum ends.

30 The use of the screen S, and its characteristic of substantial rigidity permits the employment of a simple means for controlling and regulating the flow of liquid from the drum. Any one or more of the ports 9 may be closed or choked by a 35 wad 15 of relatively yielding material held in place by the adjacent part of the screen, as illustrated in Figures 3 and 4. The wads 15 may be formed of small pieces of scrap cloth, sponge rubber or any other suitable material that can be 40 inserted through the screen openings and thereafter jammed into position. If desired they may take the form of plugs that have their inner ends pushed into the ports and subsequently held in such position by engagement of the mop with 45 their outer ends.

50 The mode of functioning of the described apparatus is believed to be fairly obvious from the foregoing description. Rotation of the drum D agitates its contents and causes the latter to emerge through as many of the ports 9 as are 55 open. The discharged material then trickles freely through the channels 10 and is distributed uniformly outwardly through the screen 5 into the mop M, which becomes uniformly impregnated or soaked with the material and applies it to the plant leaves as it wipes or rubs the latter. Addition of one or more wads 15 reduces the total output, and by proper selection of the ports to be choked the insecticide distribution may be 60 varied throughout the effective applicator area of the mop.

The channel depth is exaggerated somewhat in the drawing, and obviously may be less or greater within the scope of the invention. This and various other changes may be made without departing from the spirit of my invention, and therefore I wish to be limited, as is customary only by such restrictions as are necessarily present in the appended claims to distinguish over the prior art.

What is claimed is:

1. In combination, a dispensing drum having means for rotatably mounting it on a carriage or the like, said drum having a corrugated portion between its ends affording alternated ridges and depressions, and having apertures between certain of said ridges, a mop surrounding said corrugated portion, and means disposed between said corrugated portion and said mop to keep the latter away from the apertures and the bottoms of the depressions, said means being designed to 20 permit free outward passage of any material discharged through said apertures.

2. A device of the character described, comprising a container having peripheral end zones and a plurality of spaced channels on its outer surface between said end zones with apertures in more than one of said channels for dispensing the contents of the container, a mop covering said channels and secured in engagement with said end zones, and means for bridging said channels underneath said mop and provided with perforations greater in number than said apertures.

3. In combination, a cylindrical drum having a plurality of annular ported grooves arranged in parallelism on its periphery, a wire mesh screen surrounding all of said grooves, and a sheet of absorbent fabric snugly housing said screen and extending beyond the edges of the latter to engage the ends of the drum.

4. In the combination defined in claim 3, each groove having a plurality of ports, and means for choking at least one of the ports, said means comprising a device designed to engage the port edge and also to engage the screen.

5. A device of the character described, comprising a container having a plurality of spaced channels on its outer surface with apertures in at least some of said channels for dispensing the contents of the container, a mop covering said channels, a relatively stiff sheet of perforated material disposed between said mop and said container to bridge said channels, and means for individually and selectively closing one or more of said apertures, said closing means comprising one or more elements engaged by said sheet and pressed thereby into close association with one or more apertures.
